UNITED STATES PATENT OFFICE

167,959

LADY'S HANDBAG OR THE LIKE

Leslie L. Stucker, Bronx, N. Y., assignor to Lou Goldsmith Handbag Corp., New York, N. Y., a corporation of New York

Application July 5, 1952, Serial No. 20,466

Term of patent 14 years

(Cl. D87—3)

To all whom it may concern:

Be it known that I, Leslie L. Stucker, a citizen, of the United States and a resident of Bronx, New York, in the county of Bronx and State of New York, have invented a new, original, and ornamental Design for Lady's Handbag or the like, of which the following is a specification, reference being had to the accompanying drawing, forming a part hereof.

I claim:

The ornamental design for lady's handbag or the like, substantially as shown.

LESLIE L. STUCKER.
